UNITED STATES PATENT OFFICE

RALPH M. JENKINS, OF ORLEANS, INDIANA

SHOTGUN

Application filed May 23, 1932. Serial No. 613,072.

This invention relates to improvements in shot guns and particularly to triple barreled shot guns.

The invention is illustrated in the accompanying drawings, in which—

Fig. 1 represents a side elevation of the gun; Fig. 2, a broken vertical section of the gun in break-down position; Fig. 3, a vertical cross-section along the line 3 in Fig. 2; Fig. 4, a broken vertical section corresponding to Fig. 2, but showing the gun in closed position; Fig. 5 is a horizontal section along the line 5 in Fig. 4; Fig. 6 shows a broken vertical section of the firing mechanism viewed from the opposite side from Fig. 4; Fig. 7, a broken vertical section along the line 7 of Fig. 5; Fig. 8, a horizontal section along the line 8—8 in Fig. 7, showing the selecting mechanism; Fig. 9, a broken vertical section along the line 9 in Fig. 10, showing the firing pin on the upper barrel; Fig. 10 shows a broken horizontal section along the line 10 in Fig. 6 showing the firing pin for the upper barrel; Fig. 11, a broken vertical section along the line 11 in Fig. 6, showing in detail the selecting mechanism in the position when all barrels of the gun are cocked; Fig. 12 is a broken plan view corresponding with Fig. 11; Figs. 13 and 14 show the mechanism of Figs. 11 and 12, after the left barrel has been fired; Figs. 15 and 16 show the corresponding position after the left and center (or upper) barrels have been fired; Fig. 17 is a detail view of the selector pan; Fig. 18 shows a vertical section along the line 18 in Fig. 5, shown in the ejector mechanism with the gun in break-down position, but just before the ejector mechanism has been brought into operation; Fig. 19 is a plan view of the ejector mechanism; Fig. 20 shows a vertical section along the line 20 in Fig. 19; Fig. 21, a vertical section along the line 21 in Fig. 19; Fig. 22 shows a broken view along the line 22 in Fig. 5, with the gun in a position corresponding to Fig. 18; Fig. 23 shows the mechanism of Fig. 22 with the gun in closed position; Fig. 24 shows a broken horizontal section along the line 24 in Fig. 22, showing the ejector pins; and Fig. 25 is a vertical cross-section along the line 25 in Fig. 2, showing the ar-

angement of the ejector pins within the barrels.

The shot gun is composed of a stock portion 1, and a barrel portion 2. The stock includes a conventional grip 3, trigger guard 4, lock 5, safety catch 6. The barrel portion includes a left-hand barrel 2a, a central or upper barrel 2b, and a right-hand barrel 2c. I prefer to have the barrel 2a cylindrical, barrel 2b modified or partial choke, and barrel 2c full choke.

It has heretofore been the practice in triple barreled shot guns to place two barrels above, and one below, since this permitted easier ejection of the shells. In accordance with the present invention, however, the odd barrel is placed above and between the remaining two, thereby providing a means of sighting the gun. Sights 7 and 7a may be placed upon the barrel 2b, if desired.

The firing mechanism is contained in a frame 8 comprising an upper tang 9, and a lower tang 10. The hammers 11a, 11b and 11c, corresponding to the barrels 2a, 2b and 2c, are pivoted on the pin 20, which is journaled at 17 in the side plates 19. The hammers are fired by springs, for example, compression springs 12a, 12b and 12c, acting upon the shoulders 13, as shown in Fig. 4.

The hammers are held in cocked position by the pointed noses 15 of the sears 14a, 14b and 14c, against which the shoulders 16a, 16b and 16c of the hammers are pressed by the compression springs.

The sears 14 are pivoted upon the pin 18 which is journaled in plates 19 at the sides of the frame.

The gun is preferably provided with a single-trigger 21 and an additional trigger 22 for the full choke barrel. The single-trigger operates the hammers 11a, 11b and 11c in succession, whereas the trigger 22, operates only the hammer 11c.

The trigger 22 is pivoted at 23 in the lower tang 10. It is provided on its upper portion with a pin 24 provided with shoulders 25 and 26, and an ear-portion 27. The shoulder 25 engages the sear-arm 28c of the right-hand sear 14c. The rise of the trigger 22 is stopped by the impingement of the shoulder 26 upon

the stop 29 on the safety-lug 30. When the safety catch 6 is moved rearwardly, the projection 31 forces the safety-lug 30 rearwardly, with the result that the stop 29 falls into a position above the ear 27 and prevents the pulling of the choke-trigger. The safety-lug is to be held in contact with the projection 31 by a coil spring 32 resting upon the lower tang 10. The spring 32 provides a friction 10 and catch for the safety, holding it either in open or closed position. The safety-lug 30 is pivoted at 34 in the flange 35 of the lower tang 10 and when pushed rearwardly into safety position, as shown in Fig. 6, the ear 37 15 of the safety-lug overhangs the shoulder 36 of the single-trigger 21 and prevents pulling of that trigger. When the safety-catch 6 is released, the safety-lug 30 swings forward, swinging the ear 37 rearwardly and out of 20 engagement with the shoulder 36.

The safety-lug 30 also serves to prevent involuntary firing of a second barrel during recoil of the gun. In that stage following the recoil where the gun is moving forward 25 on a rebound from the shoulder of the shooter or a recoil chamber, and the trigger is thereby pressed against the finger of the shooter, the inertia of the safety lug 30 carries it backward relatively into the same position occupied by it when in safety, and thereby prevents firing of the gun.

The single-trigger 21 is provided with a rearwardly extending flange 38, which is in constant engagement with the plate 40. A 35 selector pan 41, which pivots upon the pin 42 is carried on the plate 40. Both the plate 40 and the selector pan 41 are movably mounted, as for example, pivoted upon the pin 39, which is journaled in the selector-post 29. 40 When the single-trigger 21 is pulled, the plate 40 and the selector pan 41 are lifted and upon successive pulls of the trigger the selector pan successively engages the sear-arms 28a, 28b and 28c, thereby raising the sears 45 14a, 14b and 14c in succession and firing the hammers 11a, 11b and 11c.

The plate 40 may be maintained in contact with the flange 38 by a spring 83 fastened in the lower tang 10. The sear 14a may be held 50 up by a sear spring 84 on the lower tang 10.

The action of the selector pan is illustrated in Figs. 11-17. In Figs. 11 and 12, the position of the parts is shown with the gun fully cocked. As shown in Fig. 12, the left prong 55 of the selector pan rests below the sear-arm 28a of the left-hand sear 14a. Upon pulling of the trigger 21 the table 40 is lifted, carrying with it the selector pan 41, which engages the sear-arm 28a, thereby lowering the nose 60 15a of the sear and firing the hammer 11a. The sear 14a is provided with a sear-hook 43a, which holds the fingers of the W table 44 in horizontal position against the spring 45. When the sear 14a is raised, the spring 65 45 forces the right side of the W downwardly,

and brings the left finger 46 of the W table into engagement with the sear-hook 43b of the sear 14b. At this point the right finger 47 engages the stop 53. The W table is pivoted at 48 and is provided with a downwardly extending projection 49, which in turn is provided with a rearwardly projecting lug 50, as shown in Fig. 17. When the left finger 46 of the W table is raised, the lug 50 is swung to the left, thereby engaging the left prong 51a of the selector pan 41 and moving the selector pan into the position shown in Figs. 13 and 14.

Upon again pulling the trigger 21, the sear-arm 28b of the sear 14b is engaged by 80 the selector pan, as shown in Fig. 14, and the hammer 11b thereby fired. After the fall of the hammer 11b, the sear is pulled back by its sear spring, thereby depressing the sear-hook 43b.

The sear-hook 43b of the sear 14b in its downward progress engages the left finger 46 of the W table and draws it downwardly until it engages the stop 52, as shown in Fig. 15, the sear spring pulling down the sear-hook 43b being more powerful than the spring 45. The action of the sear-hook 43b upon the W table causes the lug 50 to move the selector pan to the right and brings it into the position shown in Fig. 16, in which the right prong of the selector pan underlies the sear-arm 28c.

Upon pulling the trigger a third time the selector pan engages the right-hand sear 14c, thereby releasing the right-hand hammer 100 11c. After firing the sear spring 54 of the sear 14c returns the sear to position, thereby pulling down the sear-hook 43c and thereby pulling the W table back to a horizontal position. The sear-hook is prevented from falling any lower by the shoulder 25 on the choke-trigger 22. The trigger itself is prevented from being pushed lower by the notch 55, which catches upon the lower tang 10, as shown in Fig. 4.

It will also be seen that, regardless of when the choke-trigger 22 is pulled, the action of the selecting mechanism is not interfered with, since the sear-hook 43c after firing simply prevents the right side of the W table 115 from rising above the left, and the firing position for the other barrels does not require that the right side be raised above the left.

The ejector mechanism of the gun is so constructed that the ejector hammer and ejector pin for the middle or top barrel 2b is elongated and operates through slots. The ejector hammers for the other barrels may operate in any conventional manner. For 120 example, as shown in Figs. 18-25, ejector hammers 56a, 56b and 56c are provided, hammers 56a and 56c being of customary dimensions, but hammer 56b being elongated to such an extent as to reach the extractor 125 130

stem 577 below the barrel 26. The ejector hammer 56b is pivoted on a pin 69, and the ejector hammers 56a and 56c are pivoted on pin 58. The ejector hammer 56b is provided at its rearward lower extremity with a notch 59.

As shown in Figs. 4 and 6, the firing hammers 11a, 11b and 11c are provided with lower ears 60a, 60b and 60c, which engage the cocking rods 61a, 61b and 61c. When the hammers are fired, the rearward ends of the cocking rods are thereby depressed by the ears 60a, 60b and 60c. The cocking rods are pivoted at 62, so that upon firing of the gun the forward end of each cocking rod is raised as its respective hammer falls. The cocking rods are respectively provided at their forward ends with hooks 64a, 64b and 64c. When the barrels 11a or 11c have been fired, hooks 64a or 64c are brought to a position, where, upon breaking of the gun, they will engage the cams 65a or 65c. The cams 65a and 65c are pivoted on the pin 58 with the ejector hammers 56a and 56c and are provided with ears 67a and 67c engaging springs, for example such as the compression springs 68a and 68c. When the gun has been fired, breaking of the gun causes the hooks 64a and 64c to engage the cams 65a and 65c and causes them to swing forward on the pin 58, thereby releasing the springs 68a and 68c against the ejector hammers 56a and 56c and forcing out the extractor stems 57a and 57c which eject the exploded shells.

When the hammer 11b has been fired, the hook 64b on the forward end of the cocking rod 61b is raised to a point where, on breakdown, it will engage the notch 59 on the ejector hammer 56b, thereby pushing the ejector hammer forwardly on the pin 69, releasing the compression spring 68b, and thereby propelling the ejector hammer forward and ejecting the shell from the barrel 2b.

The gun is likewise provided with an extractor pin 70, which may be secured rigidly in the firing mechanism, for example, in the stem 71, upon which the gun pivots when broken. The extractor pin extends through the slots 72a and 72c in the extractor stems 57a and 57c and into the slot 73b. The slots 72a and 72c are preferably complementarily notched so as to each provide one-half of the complete slot. Upon breaking of the gun, the extractor pin is pressed into engagement with the shoulders 73a, 73b and 73c of the extractor stems, at the rearward end of the slots 72a, 72b and 72c, and thereby pushes out the shells in each barrel. The distance may be regulated by the dimensions and angle of the pin, but is preferably about one-fourth inch. As a result it is possible to remove unfired shells.

When a barrel has been fired, however, the ejector hammer is brought into play and the

shells are ejected, the movement of the extractor stems being stopped by the impingement of the shoulders 74a, 74b and 74c upon the extractor pin.

The gun may be cocked by breaking. This brings the forward ends of the cocking rods into engagement with the shoulder 76 of the frame 75 carrying the ejector mechanism, thereby elevating the rearward end of the cocking rods and forcing the hammers into cocked position.

When the gun is closed, the extractor stems 57a, 57b and 57c are pressed back into position by the extractor pin 70 which engages the shoulders 74a, 74b and 74c. The extractor stems engage the ejector hammers 56a, 56b and 56c and force them back into position on the compression springs 68a, 68b and 68c. The cams 65a and 65c, being rigidly connected with the corresponding ejector hammer, are likewise moved back into position for release on subsequent breaking of the gun.

The gun may be provided with a lock 5, operating against a compression spring 90. The handle of the lock may be rigidly secured to a pin 91, as shown in Fig. 5, which is provided at its base with an eccentric 77, so arranged that upon turning, the plate 78 is forced rearwardly, thus freeing the openings 79 and 80, by releasing the lugs 81 and 82 as shown in Fig. 22, and freeing the gun for break-down.

The gun is provided with customary firing pins 80a and 80c, but it is preferred to provide a diagonal downwardly directed firing pin 80b for the upper barrel, thereby permitting the hammer 11b to be somewhat shorter, providing a more compact and stronger mechanism.

The foregoing detailed description has been given for clearness of understanding only, and no unnecessary limitations should be understood therefrom, but the appended claims should be construed as broadly as permissible, in view of the prior art.

I claim:

1. In a triple barreled shot gun having two barrels in one plane and the third barrel in a parallel plane and between the other two, means for extracting shells from said third barrel operating between the other barrels of said gun, and in advance of the rear end of the barrels.

2. In a triple barreled shot gun comprising an upper and two lower barrels, means for ejecting shells therefrom which comprises an elongated ejector hammer located between the lower two barrels, and two relatively short ejector hammers below said barrels, and means for springing said hammers.

3. In a triple barreled shot gun having two barrels in one plane and the third barrel in a parallel plane above and between the other

two, means for ejecting shells therefrom which comprises an elongated ejector hammer located between the lower two barrels, and two relatively short ejector hammers below said barrels, and means for springing said hammers after firing said gun.

4. In a triple barreled shot gun having two barrels in one plane and one barrel in a parallel plane above and between the other two barrels, an elongated extractor pin located between the two barrels, extractor stems for each barrel located below the upper barrel and between the lower barrels and in contact with the extractor pin, and means for propelling said stems with said extractor pin on break-down of said gun.

5. In a triple barreled shot gun comprising an upper and two lower barrels, means for partially extracting unfired shells therefrom comprising extractor stems between the lower barrels of said gun and an extractor stem below the upper barrel of said gun, and an elongated extractor pin secured in the frame of said gun and engaging said stems, whereby on break-down of said gun said extractor stems are pushed a relatively short distance out of said barrels.

6. Apparatus as set forth in claim 5, in which the extractor stems between the lower barrels of said gun are slotted, and said extractor pin passes through said slots.

7. Apparatus as set forth in claim 5, in which said lower extractor stems are complementally notched, and said extractor pin passes through said notches.

8. Apparatus as set forth in claim 5, in which said upper extractor stem is slotted and said extractor pin extends into said slot.

40 9. In a single-trigger mechanism comprising a selector mechanism movable into two firing positions by a table, means for moving said selector mechanism into a third firing position.

45 10. A shot gun comprising three barrels, a hammer for each barrel, a single-trigger, a selector mechanism operated by said trigger, said selector mechanism being movable into three firing positions; sears connecting said hammers to said selector mechanism, each of said sears being located so as to be operated by said selector mechanism when it is in only one of said firing positions; and means controlled by said trigger for successively moving said selector mechanism into said three firing positions, said means comprising a pivotally mounted table connected to said selector mechanism and controlling its position, a sear hook connected to one of said sears and adapted to maintain said table in a position corresponding to the first firing position of said selector mechanism until operation of said sear, a second sear hook connected to a second sear and adapted to maintain said table in a second position corre-

sponding to the second firing position of said selector mechanism after operation of said first sear and until operation of said second sear, a third sear hook connected to said third sear and adapted to maintain said table in a third position corresponding to the third firing position of said selector mechanism after operation of said second sear and until operation of said third sear, and means for returning said table to its original position after operation of said third sear.
